MAGNETOSTRICTIVE TRANSDUCER LAMINATION

John D. Wallace, Oreland, Pa.

Application December 10, 1952, Serial No. 325,241

6 Claims. (Cl. 340—9)

(Granted under Title 35, U. S. Code (1952), sec. 266)

The invention described herein may be manufactured and used by or for the Government of the United States of America for governmental purposes without the payment of any royalties thereon or therefor.

The present invention relates to the fabrication of an electroacoustic transducer and more particularly to a magnetostrictive transducer lamination, the configuration of which is shaped like a wagon wheel.

Use of the magnetostriction phenomenon at high frequencies has been restricted due to the limitations of physical size of the transducer elements. Tubes and plates and simple ring transducers that are resonant at frequencies over 100 kilocycles have been used but with little success.

The main disadvantage of the above-mentioned magnetostrictive elements is the small physical size of the resonant systems in such transducers. Small resonant systems greatly reduce the input power and absolute sensitivity permissible. A cylindrical magnetostrictive transducer element consisting of ring laminations or a scroll winding of tape capable of resonating at 120 kilocycles or more has a diameter slightly less than 0.5 inch. As a result of this size the wall thickness of the magnetostrictive structure is very small and the impressed magnetizing force or signal exceeds, at a low power level, the critical limit set by linearity and efficiency. Conversely, such a small element intercepts so little energy in the sound wave that there is a small quantity of energy available after conversion from sound to electrical energy. An array of small transducer elements can be designed but the mounting problem becomes difficult since mounting structures tend to absorb a major portion of the transmitted or received energy.

In contrast to the cylindrical element, the transducer element hereinafter described resembles two concentric cylinders connected by radial spokes having a diameter of approximately 2.6 inches yet having a high resonant frequency, namely 130 kilocycles. An element is composed of a plurality of wagon-wheel shaped laminations providing a resonant element having a high natural frequency that is physically large for frequencies of small wave lengths.

One object of the present invention is to improve the operating characteristics and fabrication of electroacoustic transducers.

Another object of the present invention is to provide an electroacoustic transducer that is physically large but capable of resonating at frequencies of small wave lengths.

Still another object of the invention is to provide a transducer that produces high-frequency acoustic waves with a uniform response pattern in one plane.

A still further object of the invention is to provide a transducer that produces an uninterrupted alternating flux path.

These and other objects of the invention and the various features and details of construction and operation

2

thereof are hereinafter more fully set forth and described with reference to the accompanying drawings in which like numbers refer to like parts.

Fig. 1 is a view of a wagon-wheel type lamination of the invention.

Fig. 2 is a perspective view of a stack of laminations of Fig. 1 forming a magnetostrictive element.

Fig. 3 is a sketch representing the principle involved in a two-mass, one-spring system.

10 The general shape of the lamination 11 having twelve equally spaced slots or windows 13 as shown in Fig. 1 resembles a wagon wheel. It can be punched from any magnetostrictive material such as 2V "Permendur," by means of a suitable machine. In one construction, the laminations 11 are punched from clean strip stock of 0.006-inch thick, half-hard 2V "Permendur" approximately 2.75 inches wide. The characteristic frequency of half-hard 2V "Permendur" of 0.006-inch thickness is about 140 kilocycles. Said laminations are then cleaned and heat-treated for one hour in a dry hydrogen atmosphere of 500 degrees centigrade. A coating of "Cycleweld" C-3 is sprayed on both sides of the laminations to provide interlamination insulation.

To fabricate a magnetostrictive element or core 17, the laminations are stacked into a packet one inch in height (see Fig. 2). With the aid of a suitable jig and "Cycleweld" plasticized cement said laminations can be consolidated. Pressure-release material 23 such as corprene, is cemented to the inside ring surface 21 and around the 20 legs or spokes 15. Suitable mounting means (not shown) can be designed to house said element 17.

The 2V "Permendur" laminations are operated at remanence after being annealed to a magnetically half-hard state. (Greater sensitivity can be obtained by using D.-C. 35 polarized soft nickel.) Coils 19 are wound on alternate legs 15 of the core 17 and are connected in series in such polarity that the flux contributions from adjacent legs add in the bare legs. Thus, each leg is effectively polarized to the same degree when leakage is disregarded.

40 In the operation of the device, the laminations can be visualized to be composed of a group of resonant systems as shown in Fig. 3. A single spoke 15 with its inner and outer mass can most readily be compared to a two-mass, one-spring system with a node 31 at the 45 middle of the spring 39. A radiating face or surface 33 on mass 35 operates into a medium or load 37. The size of mass 35 is determined in conjunction with spring 39. The lower half of the system below the nodal line is similar to the upper half of the system with the exception 50 that radiating face or surface 41 of mass 43 operates into a pressure-release material 45. The lower half of the system provides a resonator termination for the upper half. Alternating flux in coils 19 induce a change in 55 the length of the spring 39 which in turn moves masses 35 and 43 due to the magnetostrictive effect. Thus, the energy is reflected in the lower half of the system because of pressure-release material 45 and in the upper half of the system the energy is transferred to medium 37 at face 33.

60 In an alternate construction of the invention, the radiating surface of the element 17 can be reversed by cementing pressure-release material 23 to the outer ring surface of the core instead of to the inside ring surface 21 as shown in Fig. 2. This is readily seen to be the equivalent of reversing the radiating surfaces 33 and 41 of Fig. 3. Such a construction would be suitable for the fabrication of high-frequency piston-type transducers.

From the foregoing discussion it can be seen that the 70 wagon-wheel type element provides means for producing a high-frequency acoustic wave having a uniform response pattern in one plane with an uninterrupted al-

ternating flux path. A transducer composed of wagon-wheel laminations is of simple design and construction. Such a transducer has a resonant frequency of 130 kilocycles but is physically large to permit interception and transmission of large quantities of energy.

While a particular embodiment of the invention has been shown and described herein, it is not intended that the invention be limited to such disclosure, but that changes and modifications can be made and incorporated within the scope of the claims.

What is claimed:

1. A transducer element comprising a plurality of thin wagon-wheel magnetostrictive laminations, said laminations being arranged in a face-to-face relationship insulated from each other, means for consolidating said laminations to form a first cylinder and a second cylinder concentric with such first cylinder radially separated from each other by equally spaced radial spokes, pressure-release material coextensive with and affixed to the ring surface of one of such cylinders and cemented to said spokes, and a coil electromagnetically coupled to said spokes.

2. A transducer element comprising a plurality of thin wagon-wheel magnetostrictive laminations, said laminations being arranged in a face-to-face relationship insulated from each other, means for consolidating said laminations to form a first cylinder and a second cylinder concentric with such first cylinder radially separated from each other by equally spaced radial spokes, pressure-release material coextensive with and affixed to the inside ring surface of such first cylinder and cemented to said spokes, and a coil electromagnetically coupled to said spokes.

3. A transducer element comprising a plurality of thin wagon-wheel magnetostrictive laminations, said laminations being arranged in a face-to-face relationship insulated from each other, means for consolidating said laminations to form a first cylinder and a second cylinder

concentric with such first cylinder radially separated from each other by equally spaced radial spokes, pressure-release material coextensive with and affixed to the outside ring surface of such second cylinder and cemented to said spokes, and a coil electromagnetically coupled to said spokes.

4. A compressional-wave translating device comprising a core of wagon-wheel configuration including two concentric cylinders and equally spaced radial spokes connecting said cylinders, said cylinders and radial spokes being of magnetostrictive material, pressure-release material coextensive with and affixed to the inside ring surface of said core and cemented to said radial spokes, a coil magnetically coupled to said core, and means for mounting said core.

5. The invention as described in claim 4 wherein said core consists of a plurality of thin wagon-wheel shaped laminations of magnetostrictive material consolidated into a packet, said laminations arranged in a face-to-face relationship insulated from each other.

6. A compressional-wave translating device comprising a core of wagon-wheel configuration including two concentric cylinders and equally spaced radial spokes connecting said cylinders, said cylinders and radial spokes being of magnetostrictive material, pressure-release material coextensive with and affixed to the outside ring surface of said core and cemented to said radial spokes, a coil magnetically coupled to said core, and means for mounting said core.
